UNITED STATES PATENT OFFICE.

HOMER C. LA BATT, OF CHICAGO, ILLINOIS, ASSIGNOR TO WILLIAM J. HERRICK, OF CHICAGO, ILLINOIS.

REGISTERING DEVICE FOR SHEET-FEEDING MACHINES.

1,087,245.

Specification of Letters Patent.

Patented Feb. 17, 1914.

Application filed June 27, 1904. Serial No. 214,238.

To all whom it may concern:

Be it known that I, HOMER C. LA BATT, a citizen of the United States, residing at Chicago, in the county of Cook and State of Illinois, have invented certain new and useful Improvements in Registering Devices for Sheet-Feeding Machines, of which the following is a specification.

My invention relates to a side register mechanism adapted to be associated with machines for transferring or delivering sheets of paper to a printing press, folding machine, ruling machine, or other machines employing or acting on sheets of paper, and it has for its object to provide a simple and effective mechanism of this character for alining or registering the sheets of paper so as to secure accurate results in the operation of the associated machine on the sheets delivered thereto by the feeding machine.

Another object of the invention is to provide suitable mechanism controlled by the registering mechanism for automatically tripping or throwing out of operation the associated machine, when no sheet is present, or in the event that the sheet is so far displaced as not to be acted on by the side registering mechanism.

Other objects and advantages of the invention will be apparent from the accompanying specification.

The invention consists of the combinations, arrangements, and organizations of parts hereinafter particularly described and then pointed out in the appended claims.

In the accompanying drawings—Figure 1 is a top plan view of the rear or delivery end of a machine for delivering or transferring sheets to a printing press or other associated machine and showing my invention, as embodied in one form, adapted thereto; Fig. 2 is a section on the line 2—2 of Fig. 1 showing the side registers in front elevation; Fig. 3 is a side elevation of the construction illustrated in Fig. 1, and showing a cam mechanism for moving the register in one direction; Fig. 4 is a side elevation partially in section of the mechanism for operating the side registers; Fig. 5 is an inner side elevation of one of the side registers; Fig. 6 is a detail of the gripper employed with each side register; Fig. 7 is a detail of one end of the spring and one of the wear plates shown in Fig. 14; Fig. 8 is a front elevation of one of the side registers showing the position of

the gripper at the limit of outward movement of the register, the parts being in their initial positions; Fig. 9 is a similar view showing the register at the limit of inward movement and the position of the gripper just before the latter is moved into its gripping position; Fig. 10 is a corresponding view showing the position of the gripper at the beginning and until nearly the end of the return movement of the register; Fig. 11 is a similar view showing the register just before it reaches the limit of return movement and as the gripper engages the stop and is tripped to release the sheet; Fig. 12 is a rear elevation of the side register; Fig. 13 is a section on the line 13—13 of Fig. 12; Fig. 14 is a top plan view, broken away at the center to facilitate illustration, showing a modification of the invention; Fig. 15 is a section on the line 15—15 of Fig. 14, showing the side registers in front elevation, one of them being connected up for operation while the other is disconnected and out of operation; Fig. 16 is a side elevation of the construction shown in Fig. 14; Fig. 17 is a top plan view of one of the side registers shown in Figs. 14 and 15, the jaws being broken away to show the arrangement of the gripper and connecting link; Fig. 18 is a detail view of the carrier partially in section and showing a modified form of gripper. Fig. 19 is a diagrammatic view of the mechanism for tripping the press cylinder and the electrical connections therefor; and Fig. 20 is a side elevation of the tripping device.

The side register may be employed with or adapted to any suitable or preferred machine designed to transfer sheets of paper to an associated machine, such as a printing press, folding machine, ruling machine, or other machine employing or operating on sheets of paper. For example, it may be employed with the sheet feeding machine shown in an application for United States Letters Patent filed by me March 8, 1904, Serial No. 197,083, in which the subject-matter of the present case, except the modification illustrated in Figs. 14 to 18 inclusive, was originally presented and then divided out and incorporated as part of the present case. The character and construction of the feeding machine with which my side register is associated is, however, not material.

To illustrate the present embodiment of the invention I have shown the same in

Figs. 1, 2, 15 and 16 in connection with the delivery or rear end of a suitable feeding machine, a indicating the rear roller carrying the feeding tapes a^1 , the said roller being journaled at its ends in boxes or brackets a^2 , a^3 , carried by the side bars or rails a^4 of the feeding machine. The sheets of paper pass from the rear end of the tapes a^1 to a delivery device which may consist of fingers a^5 , which when the feeder is associated with a printing press project over the cylinder a^6 thereof, certain of such fingers being provided with extensions a^7 in position to be engaged by the press gages a^8 , as shown in Figs. 1 and 3. The fingers a^5 are mounted upon brackets a^9 carried by a cross bar a^{10} which is secured at its ends to the brackets a^2 , a^3 , the brackets a^9 being adjustably secured to the cross bar as by means of set screws a^{11} . The delivery fingers a^5 are in substantially the same plane as the upper surface of the tapes a^1 . Instead of the fingers a^5 shown in Figs. 1 and 3, the delivery device may consist of a plate or delivering board a^{12} secured at its ends to the side brackets, as shown in Fig. 16, such plate extending the width of the machine and occupying substantially the same position as the fingers a^5 .

Associated with the feeding machine is suitable mechanism for registering the sides of the sheets so as to place the same as they pass from the tapes a^1 , in predetermined position for proper alinement with the operating part of the associated machine, such as the form of a printing press, for example. This side register, designated in general by the letter S , is shown in detail in Figs. 5, 8 to 13 inclusive, 15, 17 and 18, and comprises, generally, a gripping device adapted to engage the side edge of the sheet and move the same laterally to adjust it into its predetermined position. The side register is supported in any suitable manner preferably at a suitable distance from the rear of the feeder, as for example by the cross bar a^{10} (Fig. 2) and is so positioned upon such bar as to grip the paper according to the width of the stock employed.

The gripper comprises a body s mounted on the cross bar a^{10} and having a passage through which the said bar extends. The body s is intended to be adjustably mounted on the bar a^{10} to provide for adjustment of the side register, and to permit of its being readily moved and yet to prevent accidental displacement thereof in the operation of the register, as hereinafter described, it is held against movement as by a leaf spring s^1 , the ends of which engage the under face of the cross bar a^{10} . This spring is held in position by a yoke s^2 on the bottom of the body and has its tension varied by means of a set screw s^3 passing through the yoke s^2 and engaging the spring, as shown in Fig.

11. The body or block s is provided on its upper face with a longitudinal groove s^4 (Fig. 5) in which slides a vertically disposed carrier comprising a plate s^5 provided with a pair of horizontally disposed parallel jaws s^6 , s^7 , suitably spaced and connected at their outer edges by a web s^8 against which the paper is squared. The jaw s^6 is preferably extended inwardly in order to provide a relatively large table to receive one edge of the sheets from the tapes, while the jaw s^7 may be relatively short, as shown in Figs. 8 to 12. The jaws s^6 , s^7 are so disposed that the upper face of the jaw s^6 is in the plane of the tapes a^1 and in order to insure the sheet entering between the jaws they are arranged divergently or flared outwardly toward the front end of the machine, as at s^9 , as clearly shown in Fig. 5. Pivotally mounted on the carrier s^5 is a suitable gripper adapted to co-act with one of the jaws, as s^7 , to grip the paper. This gripper s^{10} may be made in the form of a bell crank lever, as shown in Fig. 6, pivoted as at s^{11} on the carrier and having its upper arm provided with a hammer s^{12} , which is movable through an aperture, shown in Fig. 8 in the lower jaw s^6 to engage the upper jaw s^7 , its range of movement in the opposite direction being limited by a stop s^{13} fixed on the slide s^5 in such position as to arrest the finger when the face of the hammer is flush with or below the surface of the jaw s^6 . The lower arm s^{14} of the gripping finger is pivoted as at s^{15} to a clip s^{16} adjustably connected to a reciprocating rod s^{17} through the medium of which motion is communicated to the gripping finger and the slide s^5 . The movement of this slide s^5 is limited in its outward throw by a stop s^{18} of any suitable form, as a screw passing through an ear on the rear face of the block, and in its inward throw by a suitable stop such as the screw s^{19} , passing through an ear on the rear face of the block and adapted to be engaged by a lug or projection s^{20} on the slide, these set screws being held by suitable locking nuts, all as clearly shown in Figs. 8 and 12. In practice I prefer to form these stops by means of the adjustable screws for the reason to be hereinafter stated. In order to prevent movement of the slide s^5 until after the gripping finger has been rocked on its pivot to grip the sheet at the beginning of the return stroke of the register, the resistance to movement of the slide s^5 is increased by means of a leaf spring s^{21} located in a chamber or recess s^{22} formed in the block s and adapted to bear at its ends against the face of the slide s^5 . To avoid wear of the slide s^5 by the ends of the said spring, wear plates s^{23} are provided and retained in position by pins s^{24} extending from the said plates and entering slots s^{25} in the ends of the spring, 130

as shown in Figs. 7 and 13. The tension of the spring s^{21} may be adjusted by means of a set screw s^{26} which passes through the wall of the block s and engages the said spring. In order to permit of the adjustment of the side register in accordance with the position of the form of the press and the width of the sheets, the clip s^{16} is clamped to the rod by bolts s^{27} or other suitable means, and by loosening these securing bolts the side register may be adjusted to any desired position by overcoming the resistance of the spring s^1 .

Preferably associated with the register is a gage plate s^{28} which is designed to be engaged by the sheet of paper at a point of predetermined alinement. This gage plate is carried by a suitable inwardly extending arm s^{29} attached by suitable screws to the rear side of the block s , as shown in Fig. 12, and extends vertically beyond the outer end of the said block, the jaws s^6 , s^7 being recessed at their outer edges as at s^{30} to permit the web s^8 to move past the gage plate so that the latter prevents the sheet being carried out of register after being released by the gripping finger and during the final movement of the jaws, and this gage is so located as to be engaged by the sheet simultaneously with the release of the latter by the gripping finger.

The rod s^{17} to which the side register s is connected and by which it is reciprocated is controlled by any suitable mechanism, such for example as that shown in Figs. 1, 3 and 4. In the construction there illustrated the bracket a^2 is provided with a suitable way p in which is mounted a slide p^1 provided with a pin or stud p^2 coöperating with a cam as hereinafter explained. The rod s^{17} may be attached directly to the slide p^1 , but in order to provide for a simple and precise adjustment of the side register the said rod passes through an aperture in the bracket a^2 and is attached to an arm p^3 through which freely passes a screw p^4 having threaded adjustment in the outer end of the slide p^1 . In order to prevent movement of the arm p^3 along and independently of the screw p^4 the latter is provided with an annular groove p^5 , shown in dotted lines in Fig. 1, to receive the end of a pin or screw p^6 passing through the arm. While the alinement of the gage s^{28} may be made approximately exact by moving the block s by hand, by turning the screw p^4 , it may be moved to secure a fine and exceedingly accurate adjustment of the said gage.

Mounted on the upper face of the bracket a^2 , in a suitable way p^7 , is a slide p^8 provided with a cam slot p^9 disposed so as to receive the pin or stud p^2 of the slide p^1 .

As shown in the present construction the cam plate is attached to one end of a rod p^{10} which is provided with a pin p^{11} . Fixed to

the adjacent end of a shaft p^{12} , which is suitably journaled on the frame a^4 , as shown in Fig. 3, is a cam disk p^{13} provided with a depression p^{14} . Pivoted at its lower end on the frame a^4 , as at p^{15} , is an arm p^{16} having at its upper end a slot p^{17} into which extends the pin p^{11} . The arm p^{16} is provided with an antifriction roller p^{18} disposed in the plane of movement of the cam. The cam p^{13} is designed to move the cam slide p^8 outwardly to return the side register after its inward movement, while a spring p^{19} advances or moves the register inwardly after each impulse of the cam. The spring p^{19} is shown as an expansion spring coiled about a stem p^{20} fixed on a plate p^{21} on the bracket a^2 and passing freely through an aperture in a lug p^{22} on the slide, so as to react between the said plate and the lug. The spring holds the arm p^{16} in operative relation to the cam. The action of the side register is designed to be rapidly accomplished and to this end the recess p^{14} extends only a short distance in the cam which extends nearly the whole of the periphery of the disk to hold the register normally retracted and stationary. When the recess in the cam comes into alinement with the arm, the spring p^{19} moves the register operating rod s^{17} inwardly and the operation is then completed by the antifriction roller p^{18} passing upon the cam p^{13} again so as to return the rod outwardly.

The feeding machine may have associated with it a suitable device designed to square or gage the front or advancing edge of each sheet. In the present construction I have shown this registering device (Figs. 1, 3 and 4) as in the form of a plate F which is periodically and automatically lowered into the path of the advancing sheet of paper and is then raised after the front edge of the paper has been alined with the gages of the press, this squaring action being preliminary to the registering of the sheet by the side register. The plate F in its operative position occupies a vertical position in the path of the paper, as shown in dotted lines in Fig. 3, and is carried by a pair of arms f^1 fixed to a rock-shaft f^2 journaled at its ends in suitable bearings f^3 carried by the brackets a^2 , a^3 , as shown in Fig. 1. The plate F is lowered through the medium of a suitably operated slide f^4 , mounted on the bracket a^3 , to which is connected a link f^5 also connected to a crank arm f^6 fixed on the rock-shaft f^2 , as shown in Fig. 1 and is elevated by springs f^7 coiled about the rock-shaft and anchored to the arms f^1 and the bearings f^3 .

In the operation of the side register S the sheets carried by the tapes a^1 enter between the jaws s^6 , s^7 , in position to be engaged by the web s^8 preferably near the end of the inward movement of the carrier, it being obvious, however, that the sheets will be en-

130

gaged and registered if upon the lower jaw at any point within the range of movement of the carrier. The sheet is first engaged at its front edge by the gage F, which having placed the sheet in proper alinement, is then raised out of the path of the sheet. The sheet is then carried by the tapes a^1 to the press gages, which at this point in the operation rest at their ends on extensions a^7 of the fingers a^5 of the delivery device, as shown in Fig. 3, arresting and gaging the sheet in the usual manner. As soon as the sheet has been arrested by the press gages the recess in the cam p^{18} comes into register with the antifriction roller p^{18} , permitting the spring p^{19} to expand and move the cam slide p^8 rearwardly, and in the direction of the feathered arrow Fig. 4, so as to move the rod s^{17} in the direction of the arrow shown in Figs. 8 and 9. At the beginning of this movement the parts are in the positions shown in Fig. 8, with the gripping finger s^{10} depressed and resting against the stop s^{13} . This movement of the rod s^{17} , by reason of the gripping finger s^{10} reacting against the stop s^{13} , causes the inward movement of the slide s^5 , thereby thrusting the web s^8 against the edge of the sheet between the jaws so as to move the sheet laterally and inwardly. The positions of the parts of the register at the inward limit of movement are shown in Fig. 9, with the gripping finger still resting against the stop s^{13} . As soon as the rod s^{17} , and consequently the register, reaches the limit of inward movement, such movement being in practice about an inch and a quarter, the slide p^8 is by the action of the cam p^{13} returned to its initial position, moving in the direction of the featherless arrow, Fig. 4, and returning the rod s^{17} . The initial movement of the rod s^{17} in this reverse or outward direction indicated by the arrow Figs. 10 and 11, causes the gripping finger s^{10} to turn on its pivot s^{11} from the position shown in Fig. 9 to that illustrated in Fig. 10, or until it contacts with and is stopped by the upper jaw s^7 , thus providing a slight amount of lost motion between the rod s^{17} and the slide s^5 . When the finger is arrested by the upper jaw s^7 the rod s^{17} still continuing its movement, the said rod and the slide s^5 are caused to move together until the end of the arm s^{14} contacts with the stop s^{18} , as shown in Fig. 11, and as the sheet was in the path of the hammer when the latter was rocked on its pivot the sheet is carried outwardly by the coöperation of the finger and the jaw s^7 . At the moment that the lower end of the finger contacts with the stop s^{18} in the reverse or outward movement of the slide s^5 , the inner face of the web s^8 is in alinement with the gage plate s^{28} , at which instant the sheet is in its predetermined alined position. In order to now release the sheet from the grip

of the parts, when the lower arm of the gripper engages the abutment s^{18} , as shown in Fig. 11, the finger is tripped out of engagement with the jaw s^7 by being rocked in its pivot s^{11} , by reason of the continued reverse or outward movement of the rod s^{17} , during which movement the slide s^5 continues its movement owing to the connection of the abutting finger with the two parts until it reaches the position shown in Fig. 8, which is the limit of the outward movement of the parts. The press gages are now moved out of the way and the sheet is taken by the grippers of the press cylinder, in the usual manner. The cam slot p^9 defines the range of movement of the slide s^5 , and the abutments s^{18} , s^{19} are adjusted to correspond with the range of movement provided for by the cam slot. These abutments are made adjustable in order to prevent overthrow or lost motion due to wear of the parts.

Only one register S need be employed in order that the impressions on both sides of the sheets may register with each other in case the sheets are cut with accuracy so that the side edges are parallel. Under other conditions and in order to accommodate the machine to variations in stock, etc., a second register S' is employed and located at the opposite side of the machine so as to register the sheets from the same side edge for the second impression as for the first impression. To secure the best results it is desirable to have the two side registers grip the sheet at the same point between its ends and the register S' is therefore preferably mounted on the cross bar a^{10} and located at the side of the machine opposite to the register S, as shown in Figs. 1 and 2. The register S' is of the same character, construction and operates in the same manner as the register S. The register S' is operated by a rod t , connected thereto in a manner corresponding to the rod s^{17} with the register S, and which rod t is connected to a slide t' similar to the slide p' and in the same manner as shown in Figs. 1, 3 and 4. The slide t' is disposed parallel with the slide p' and moves in a way formed in the upper face of the block a^2 . It is actuated by a pin entering a cam slot t^2 formed in the cam slide p^8 , such cam slot t^2 being disposed at an angle and reversely to the slot p^9 so that the same mechanism for operating the register S may be employed for operating the register S'. As these registers are designed to be operated independently of each other, only one of them operating at any time, the connecting pin p^2 is designed to be used with either slide, being removably inserted therein. Assuming that the sheets are to be alined by the register S at one edge in making the impression on one side, the pin p^2 is placed on the side p' and the register op-

erated in the manner already described. When the sheets have been run through the press they are turned over so that the same side edges before adjacent the register S are 5 now disposed adjacent the register S' . The pin p^2 is then removed from the slide p' throwing the register S out of operation and is inserted in the slide t' thereby operating the register S' so that the sheets will be 10 registered from the same side edges for the impression upon the other face and insure the impression upon both faces being in exact register.

The invention may be variously modified 15 and embodied in other forms than that heretofore described. For example, I show in Figs. 15 to 18, inclusive, a construction in which but one reciprocating rod is employed for actuating both side registers when two 20 such registers are employed. The side registers, which are here designated S^2 and S^3 , except in the details hereinafter specified, are substantially the same as that heretofore described, and are likewise mounted to slide 25 on a cross bar c attached at its ends to brackets c^1 , c^2 , corresponding to the brackets a^2 , a^3 . In this construction I have shown a slightly modified form of gripping finger, comprising a bell crank lever d pivoted at d^1 on the 30 slide s^5 , the hammer designed to be moved into and out of engagement with the upper jaw s^7 of the register, taking the form of a stem d^2 movable in a sleeve d^3 on the slide s^5 and through an opening in the lower jaw s^6 , 35 the said stem having an opening or slot into which extends the end of the upper arm of the lever d , as shown in Fig. 18. It is obvious that as the bell crank lever is rocked the stem will be raised or lowered to move 40 into and out of engagement with the jaw s^7 . Slidably mounted in apertures (not shown) in the brackets c^1 , c^2 , is a cross rod d^4 , and the registers S^2 , S^3 , are so constructed and arranged as to be capable of being connected 45 or attached to this rod so that either may be thrown into and out of operation at will, depending upon from which side of the feeder the sheets are to be registered. This may be worked out in any suitable manner 50 adapted to the attainment of the desired end. In the present instance each gripping finger d has pivoted thereto, as at d^5 , a link d^6 the free end of which is provided with a hook d^7 . As shown in Figs. 2 and 16, the side 55 registers are made rights and lefts, and the links as shown in Fig. 15 extend inwardly when connected up for operation. This however is not material. Suitably supported from the rod d^4 are pins or studs d^8 , one associated with each register and adapted to receive the hooked end of the link of such register. Preferably each pin is carried by a clip d^9 , similar to the clip s^{16} , and adjustably secured upon the rod by bolts d^{10} for 60 the same reason as the clip s^{16} . From an in-

spection of Fig. 15 it is apparent that by coupling or uncoupling the hooked links of the registers with the pins d^8 of the clips either register may be thrown into or out of operation at will. Any suitable mechanism 70 may be employed for reciprocating the rod d^4 as by that illustrated in Figs. 14, 15 and 16. As shown the bracket c^1 is provided with a way d^{11} in which is adapted to reciprocate a slide d^{12} having a downwardly projecting ear d^{13} having an aperture through which passes the adjacent end of the rod d^4 , the latter being threaded to receive locking and adjusting nuts d^{14} to secure the ear rigidly to the rod. The slide d^{12} is provided on its upper face with a pin d^{15} , which is engaged by a slot d^{16} in an arm d^{17} of a double bell crank lever d^{18} . This lever is pivoted as at d^{19} on the bracket c^1 and is provided with a pair of laterally and oppositely extending arms d^{20} , d^{21} . Suitably mounted on the frame of the feeding machine so as to reciprocate longitudinally thereof is a rod d^{22} provided at its end adjacent the lever d^{18} with a yoke d^{23} one of the arms of which, as d^{24} , is adapted to be pivotally connected to one of the arms, as d^{20} , of the lever d^{18} , while the other arm, d^{25} , is adapted to be pivotally connected to the other arm, d^{21} , of the lever. A convenient manner of providing this pivotal connection is by forming the associated arms with apertures d^{26} to receive a removable coupling pin d^{27} . The rod d^{22} may be reciprocated by any suitable mechanism such as that shown in connection with the construction first described. The initial movement of each side register being inwardly it only depends on the connection of the proper arm of the bell crank lever d^{18} with its associated arm of the yoke to secure such movement. In Fig. 15 the left hand register or S^2 is connected up for operation and in Fig. 14 the arm d^{20} is pivotally connected to the arm d^{24} to properly operate the same. When the register S^2 is disconnected and the register S^3 connected, it is only necessary to transfer the pin d^{27} to the associated openings of the arms d^{25} and d^{21} . The operation of the register is otherwise the same as that shown in Figs. 8 to 13 inclusive. 100

Another feature of the invention is the utilization of the side registers for controlling suitable mechanism for throwing the associated machine out of operation when no sheet is delivered to the feeding machine 110 or when a sheet is so far out of alignment as not to be acted on by the active side register. The parts are so arranged that under the circumstances mentioned the engagement of the gripping finger with the upper jaw s^7 closes a circuit governing the mechanism for throwing the associated machine 120 out of operation. To this end one side of a circuit including therein a battery x and electromagnet n is connected to the frame 130

of the feeding machine or otherwise is in electrical continuity with the gripping finger of the register, as shown in Fig. 19, while the other side is connected to a contact n' , projecting through the upper jaw s^7 of the side registering device but insulated therefrom by a non-conducting sleeve n^2 (Fig. 9). The contact is in such position as to be engaged by the gripping finger when the latter is rocked on its pivot into its gripping position and no sheet is in position to be gripped thereby thus closing the circuit and energizing the electromagnet, it being understood that the sheets in the normal operation of the machine serve to insulate the gripping finger from the contact n' . The mechanism governed by the electromagnet to throw the associated machine out of operation may be of any suitable or preferred character, such as the device for operating the cylinder tripping mechanism of a printing press shown and claimed in an application for patent filed by me December 18, 1903, Serial No. 185,625, and comprising generally the following mechanism (Figs. 19 and 20). Mounted in any suitable manner on the frame of the printing press is a shaft n^3 which may be driven from the press. Adapted to be secured to the frame of the press is a bracket n^4 provided with a groove in which moves a slide n^5 having attached thereto a cable n^6 adapted to actuate the means (not shown) for tripping the press. Pivoted to the slide n^5 is a latch n^7 having a hook n^8 at the free end designed to be engaged by the shoulder n^9 of the dog n^{10} , pivoted on a disk n^{11} fixed on the shaft n^3 . The dog n^{10} is held during a portion of the rotation of the disk in position to engage the latch n^7 , when the latter is released and moves into its active position, by a cam n^{12} . The cam n^{12} is rigid with an extension n^{13} of the bracket n^4 and projects in the path on the inner end of the dog n^{10} . The latch is provided with a toe n^{14} which is engaged by the end of the armature n^{15} of the electromagnet n when the parts are in the position shown in Fig. 20. Upon the energization of the magnets by the closing of the gripping finger s^{12} against the contact n' the armature n^{15} is attracted releasing the latch n^7 whose hook is then engaged by the shoulder n^9 to move the slide n^5 and trip the press. As soon as the cylinder has been tripped the dog n^{10} passes out of engagement with the cam and owing to the resistance of the latch and the rotation of the disk is turned on its pivot so as to release the shoulder n^9 from the latch. The dog n^{10} after the disengagement of the latch n^7 in the manner described, is returned to its normal or active positions by means of a spring n^{16} . In order to reset the latch n^7 , the disk n^{11} is provided with a cam n^{17} adapted to engage an antifriction roller n^{18} on the latch

and lift the latter so that its toe n^{14} is moved out of the path of the end of the armature n^{15} which, assuming the electromagnet to have been deenergized by the opening of the circuit by the retraction of the gripping finger, engages the toe to hold the latch in its inactive position ready to be released by the closing of the circuit again.

Having described my invention what I claim as new and desire to secure by Letters Patent is—

1. In a sheet register, a reciprocating carrier, a gripper pivoted thereon, means to advance the carrier and gripper simultaneously, then move the gripper independently of the carrier and finally retract the carrier and gripper simultaneously, and an abutment engaged by the gripper during the retractive movement to move the same on its pivot.

2. In a sheet register, a reciprocating carrier having a jaw, a gripper having angularly disposed arms and pivoted at its angle to the carrier, means for advancing the carrier and gripper simultaneously, then rock the gripper on its pivot to move one of its arms into engagement with the jaw and finally retract the carrier and gripper simultaneously, and a stationary abutment which is engaged by the other arm during the retractive movement to rock the gripper on its pivot and release the sheet.

3. In a side register, a reciprocating carrier having a jaw, a stop on the carrier, a gripper movably mounted on the carrier, means to cause the gripper to re-act against the stop to move the carrier and gripper together in one direction and then to move the gripper into engagement with the jaw to move the carrier and gripper simultaneously in the opposite direction, and an abutment to coöperate with the gripper on its retractive movement to release the sheet.

4. In a side register, a reciprocating carrier provided with an upper and a lower jaw, the latter having an aperture, a stop on the carrier, a gripper pivoted on the carrier and movable through the aperture of the lower jaw, a reciprocating connection pivoted to the gripper and adapted on its advance to force the gripper against the stop to advance the carrier and gripper and on its retraction to first rock the gripper on its pivot and into engagement with the upper jaw and then to retract the carrier and gripper, and an abutment to coöperate with the gripper on its retractive movement to release the sheet.

5. In a mechanism of the class described, the combination with a pair of oppositely disposed side registers each of which is provided with a gripper, of a reciprocating rod, a link associated with each register and adapted to detachably connect the gripper thereof to the rod, a lever for reciprocating

- the rod and having a pair of lateral arms, and an operating rod having an arm associated with each of the said lateral arms and adapted to be detachably connected thereto.
- 5 6. In a sheet feeding machine, in combination with a frame provided with carrying tapes, a cross bar carried by the frame, a pair of registering devices mounted on the bar and each of which comprises a reciprocating carrier and a gripper mounted thereon, a reciprocating rod, and means associated with each register for detachably connecting the gripper of such register with the rod.
- 10 7. In a sheet feeding machine, in combination with a frame provided with carrying tapes, a cross bar carried by the frame, a pair of registering devices mounted on the bar and each of which comprises a reciprocating carrier and a gripper pivotally mounted thereon, a reciprocating rod, a pin associated with each register and adjustably carried on the rod, and a link for detachably connecting each pin with the gripper of the
- 25 8. In a machine for feeding sheets of paper to an associated machine, the combination with a device for throwing the associated machine out of operation, an electromagnet controlling the device, of a registering device comprising a pair of jaws one of which is movable, and electrical circuit connections between the jaws and the electromagnet, the movable jaw being movable into engagement with the other jaw to close the circuit when no sheet is delivered between the jaws.
- 30 9. In a machine for feeding sheets of paper to an associated machine, the combination with a device for throwing out of operation the associated machine, an electromagnet controlling the device, of a registering device comprising a reciprocating carrier having a jaw, a contact carried by but
- 35 insulated from the jaw, a gripper pivoted to the carrier, means for moving the carrier and the gripper whereby the latter is moved into contact with the jaw-contact when no sheet is delivered between the gripper and jaw, and circuit connection between the contact and gripper and the electromagnet.
- 40 10. In a machine for feeding sheets of paper to an associated machine, the combination with the device for throwing the associated machine out of action, a slide, a latch pivoted on the slide, a rotatable element, means for coupling the latch to the rotatable element, electromagnetically controlled means for holding the latch out of engagement with the coupling means, of a sheet registering device consisting of a reciprocating carrier having a stationary jaw, a contact carried by but insulated from the jaw, a gripping finger adapted to be moved into contact with the jaw-contact, and connections between the contact and the finger and the electromagnet.
- 45 11. In a machine for feeding sheets of paper to an associated machine, the combination with a device for throwing the associated machine out of action and comprising a slide, a latch pivoted on the slide, a rotatable disk, means carried by the disk to engage the latch, electromagnetically controlled means for holding the latch out of engagement with the latch-engaging means, of a sheet registering device consisting of a reciprocating carrier having a stationary jaw, a contact carried by but insulated from the jaw, a gripping finger adapted to be moved into contact with the jaw-contact, and connections between the contact and the finger and the electromagnet, and means for restoring the latch.
